DESIGN FOR AN ALPHABET FOR FORMING MONOGRAMS OR THE LIKE

Michael Chernow, Brooklyn, N. Y.

Application September 14, 1933. Serial No. 49,253

Term of patent 3½ years

To all whom it may concern:

Be it known that I, MICHAEL CHERNOW, a citizen of the United States, and residing at Brooklyn, in the county of Kings and State of New York, have invented a new, original, and ornamental Design for an Alphabet For Forming Monograms or the like, of which the following is a specification, reference being had to the accompanying drawing, forming part hereof, and in which

Fig. 1 is a plan view of an alphabet showing my new design, the letter X being omitted and the same letter serving as both the U and the V, and Fig. 2 is a perspective view of one of the letters of the alphabet.

I claim:

The ornamental design for an alphabet for forming monograms or the like, substantially as shown and described.

MICHAEL CHERNOW.
